UNITED STATES PATENT OFFICE.

JACOB HOFFMAN, OF MEMPHIS, TENNESSEE.

SHOE-POLISHING MACHINE.

Application filed March 25, 1926. Serial No. 97,205.

This invention relates to apparatus for cleaning and polishing shoes and to timing mechanism for coordinating the various steps necessary in accomplishing this.

5 The objects of this invention are,

- (a) To provide means for applying cleaning fluid;
- (b) To provide means for applying a polishing material;
- 10 (c) To provide means for cleaning the front portion of the shoe and thereafter to give a finish or polish thereto;
- (d) To provide means for shifting from the cleaning to the final polishing means;
- 15 (e) To provide means for cleaning the heel and side portions of the shoe and thereafter to give a finish or polish thereto;
- (f) To provide means for simultaneously shining the front portion of one shoe and the 20 heel and side portion of the other shoe without attention from the customer;
- (g) To provide means for shifting these various means from one shoe to another;
- (h) To provide means for coordinating the 25 various steps in accomplishing the foregoing.
- (i) To generally provide for and improve the details of construction of such machines.

These objects are accomplished as will be more fully hereinafter set out in the drawings, specification and claims.

In the drawings:

Fig. 1 is a front elevation of the machine in its preferred form.

Fig. 2 is a corresponding side elevation, with the near side of the frame cut away.

Fig. 3 is a horizontal section of the polish holder on the line III—III of Fig. 2.

Fig. 4 is a similar section of the cleaning fluid holder on the same line.

40 Fig. 5 is a plan view of the machine.

Fig. 6 is a front elevation on an enlarged scale showing the means for operating the shining belt and polishing belt and the timing means and shifting means for shifting from the shining belt to the polishing belt.

Fig. 7 is a side elevation of the mechanism shown in Fig. 6, with the shift-locking mechanism shown in section.

Fig. 8 is a fragmentary sectional elevation 50 on the line VIII—VIII of Fig. 7 showing the locking-release operating means.

Fig. 9 is a fragmentary plan view of the operating mechanism in Fig. 7, and

55 Fig. 10 is a fragmentary sectional plan on the line X—X of Fig. 6.

Fig. 11 is an elevation on approximately

twice the scale of Figs. 1, 2 and 5 showing the foot rests and means for adjusting them and the mechanism by which the operation of the machine is controlled.

60 Fig. 12 is a fragmentary side elevation of the mechanism for applying cleaning fluid and polishing paste to the cleaning and polishing belt.

Fig. 13 is a fragmentary sectional plan of the mechanism shown in Fig. 12, and

Fig. 14 is a fragmentary sectional elevation taken on the line XIV of Fig. 13.

70 Fig. 15 is an enlarged fragmentary view showing the lower end of the yoke arm and associated parts at their extreme left hand position with the releasing latch disengaged.

Fig. 16 is a similarly enlarged end view of the release operating parts.

75 Fig. 17 is a view of the same parts with the yoke arm in a shifted position and the latch engaged.

Fig. 18 is the corresponding end view of these parts.

80 Fig. 19 is an enlarged side view of a part of the foot rest supports.

Fig. 20 is a corresponding end view of these parts.

85 Figs. 21 and 22 are respectively enlarged fragmentary plan and side views of the brush-reciprocating mechanism and control.

Referring now to the drawings in which the various parts are indicated by numerals, 1 indicates the frame of the machine. 2 are cross rails extending from one side of the frame to the other on which rails the toe-shining, and polishing, mechanism is shifted to transfer from one shoe to the other. 3—3 are similar rails on which the heel-polishing mechanism is shifted transversely for the same purpose. 4—4 are side members of the carrier for the toe-shining, and polishing, mechanism. 5 are bottom members and 6 top members joining the side members 4 at their upper and lower ends respectively. 7 are rollers which are journaled in the side members 4 and which rest on the upper surface of the transverse members 2. 8 are rollers correspondingly journaled, which bear on the under side of the same members 5 these sets of rollers providing means permitting shifting of the carrier.

100 The carrier for the toe polishing mechanism will hereinafter be designated as the belt-carrier, and the mechanism as the belt-mechanism. The carrier for the heel polishing mechanism comprises longitudinal mem-

bers 9, lower and upper transverse members 10, 11, and vertical side members 12. In these vertical side members 12, rollers 13, 14 are mounted, which rollers respectively rest on the upper surface of the transverse members 3, and bear against the lower surface thereof, to provide means permitting lateral shifting of the heel polishing mechanism. The carrier for the heel polishing mechanism will 10 hereinafter be designated as the brush-carrier, and the mechanism, as the brush-mechanism.

From the lower member 5 of the belt-carrier an arm 15 extends downwardly and is provided at its lower end with a pin 16. Similarly, an arm 17 extends downwardly from the bottom member 18 of the brush-carrier. This arm 17 is also provided with a pivot pin 19, which engages with a slot 20 in one end of an arm 21, the pin 16 engaging the slot 22 in the opposite end of the same arm.

The arm 21 is pivoted on pin 23, carried by pedestal 24 extending upward from the base 25 of the main frame, so that when the belt-carrier is shifted to one side, the brush-carrier will be shifted to the opposite side. The shifting mechanism accomplishing this will be later described.

30 Shoe supports.

Extending upward from the base 25, are standards 26, 26^A, which carry a frame comprising arms 27, 27^A, and a cross member 27^B, the arms 27, 27^A being longitudinally slideable 35 in the hubs 26^B and 26^C at the upper ends of the standards 26, 26^A. The arms 27, 27^A carry hubs 28, 28^A in which is mounted a vertically slideable frame comprising posts 29, 29^A and an integral cross member 29^C. 30 are springs 40 normally forcing the arms 27, 27^A backward. Similarly the posts 29, 29^A are normally held in raised position by springs 31. The upper end of each post carries a shoe rest 32. By these various members the shoe rests 32, may 45 be adjusted both vertically and longitudinally with reference to the polishing mechanisms. It will be noted that because of the unitary construction downward movement of one foot rest causes corresponding downward movement of the other and similarly any forward movement is in unison. 33 is an indicating arm which determines the proper location of the toe of the shoe, so that the shoe to be shined, may be adjusted to the proper position. 34 is a seat. The adjustment is accomplished by placing the foot on the rest and pushing downward and forward until the upper edge of the right shoe comes against the indicator arm 33. When the shoe rests 50 have been brought to position, the indicating arm is turned outward about the center 33^A causing the rod 33^B projecting rearwardly past the bracket 28^A, to engage the lower end of the latch 33^C and force same outward thus 55 engaging the upper end of the latch with one

of the notches 29^B, locking the posts 29^A, and 29 connected therewith against vertical displacement. 33^D is a latch integral with the indicating arm 33 which is adapted to engage similar notches 27^C in the under side of the 70 arm 27^A, when the arm 33 is turned outward as above described, and to lock the arms 27^A, and 27 connected thereto against longitudinal movement.

75 Toe-polishing mechanism.

The belt-mechanism for polishing the toe of the shoe comprises a belt made up of a cleaning-belt 35 and a polishing-belt 36, which are joined at the central point, A, into a single belt, the ends of which are fastened to the half-drum 37. The drum 37 is mounted on and secured to a shaft 38, as by a set screw 39. The shaft 38 is oscillatably mounted in bearings 40, and carries on the end opposite the drum 37, a swinging arm 41, which is secured to the shaft, as by a set screw 42. The lower end of the arm 41 carries a yoke 43, which is oscillated by a crank pin 44. 45—46 are crank pin arms which are respectively provided with a journal 47 which rotates in the bearing 48, and a journal pin 49 which rotates in a bearing 50. These bearings are carried on the upper end of a yoke arm 51, which yoke arm swings about a pin 52, secured in the lower end of a post 53, which post is integral with the belt-carrier frame.

The pin 49 journals a belt-wheel 54, which belt-wheel is driven by a smaller belt-wheel 55, through a belt 56. The belt-wheel 55 has two belt grooves, and is journaled on the pin 52. 57 is a drive pulley mounted on and secured to the main driving shaft 58. 59 is a belt from the drive pulley 57 to the second groove on the belt-wheel 55. 60—61 are fixed stops projecting from the frame member 5 which limit the swinging motion of the yoke arm 51. 62 is a locking member, retractably mounted in the post 53 and adapted to engage lugs 63—64, projecting from the yoke arm 51 and thereby hold the yoke arm in either of two positions.

At the upper end of the swinging or yoke arm 41, are pins 65—66 spaced equal distances above and below the shaft 38, on which pins ratchet arms 67—68 respectively are mounted, these being more clearly shown in Figs. 6 to 9 inclusive. 69 is a tension spring connecting these arms, and 70, 71 are pins carried by an extension 72 from the upper belt-carrier member 6, and by the member 6 respectively, which pins limit motion of these arms toward each other. 73 is a trip arm, pivotally carried by a bolt 74, on an extension 75 from the member 6. 76 is a tension spring, having one end secured to a pin 77, carried by an arm 78 extending from the member 75, and the other end engaging a pin 79, projecting from the trip arm 73. 80 is a trip yoke arm or yoke, which embraces the trip arm 73 130

and is mounted on and secured to a shaft 81, which is journalled in and is slidably movable transversely to the upper end of a tube 82, which tube is secured to the frame member 6 and to a member 83 projecting laterally from the post 53. 84, 85 are arms of a bell crank lever also mounted on the shaft 81 adjacent the yoke arm 80. 86 is a pin, projecting from an extension 87 of the trip yoke 80 into the path of the arms 84, 85 of the bell crank lever, between which arms it is positioned. Extending laterally from the bell crank lever is a dog which has ears 89, 90. 91 is a shift arm, having a yoke at its upper end embracing the shaft 81, and lying between the bell crank lever arms 84, 85 and the tube 82. This arm is pivoted at 92 and has on the lower end thereof a roller 93 adapted, during certain movements of the yoke arm 51, to engage with, and be displaced by, a cam 96 integral with the bearing 48. 97 is a flat spring, having a forked end embracing the pin 81 and normally holding the pin and the bell crank lever arm 84, 85 carried thereby, toward the tube 82, and holding the ears 89, 90 positioned in line with trip lugs 98, 99 on the upper end of a trip rod 100, which rod is slidably mounted within the tube 82. 101 is a tension spring normally tending to hold the rod 100 raised. On the lower end of the rod 100 is a wedge-shaped cam 102 which engages a cam member 103 forcing it outward when depressed. 104 is an arm, pivotally attached to the locking member 62, and loosely pivoted to cam member 103. The outer end of the arm 104 has a lug 105 projecting inward and normally resting against, the frame member 83. 106 is a spring tending to hold the arm 104 toward the frame member 83.

108 is a shift-gear which is journalled on the member 6. This gear has teeth which are adapted for engagement by the pawl 67, or in shifted position of the pawls, by the pawl 68. 109 is a pin projecting from the gear 108 into the path of the bell crank arms 84 and 85. The halves 35, 36 forming the belt, extend downward from the drum 37 and pass over idlers 110, mounted respectively on arms 111, 112, which arms in turn are pivoted at 113, 114 on the frame 4. A spring 115 and a similar spring not visible, normally hold the arms 111, 112 down and the belt taut. A cross arm 116 extends from the arm 112 across to, and beneath the arm 111, so that the arm 111 will be raised when the arm 112 is raised. A continuation 112^A, of the arm 112, extends beyond the pivot 114 and carries a trip arm 117, which arm is provided at its lower end with a forwardly projecting lug 118.

119 is an arm, integral with and extending substantially, at right angles from the lower end of the yoke member 51, this arm having a projecting end 119^A, adapted in one position of the arm 119 to engage the lug 118. 120 is a latch oscillatably mounted on the arm 119 and having a forwardly extending arm 120^A disposed in the path of a trip member 123^A, which is integral with the arm 123, and projects upward therefrom. 121 is a bevelled wheel, which is journalled in a bracket 122, integral with and extending downward from the arm 119. 123 is an arm, pivoted to the frame member 1 and supported by a spring 124. 125 is a stop, limiting the upward movement of the arm 123. The arm 123 carries a track 126 on which the wheel 121 runs. 127 and 128 are lugs, oscillatably mounted on the arm 123, at opposite ends of the track 126, each lug having a bevelled edge 129 adapted to engage the bevelled wheel 121, whereby the lugs are deflected, thus allowing the trip 123^A to rise, strike the arm 120^A and rotate the latch 120, to disengage the lug 118, from the projecting end 119^A.

Shifting mechanism.

130 is a horizontally disposed ratchet wheel, rotatably mounted on a bracket 131, extending upward from the base 25. Engaging this ratchet wheel, is a dog 132, which is reciprocated by an eccentric 133 mounted on the main shaft 58. Projecting from the upper side of this ratchet wheel is a pin 134, which engages a slot 135 in the arm 21. Rotation of the main shaft, will therefore advance the ratchet wheel step by step and oscillate the arm 21, shifting the belt-carrier and the brush-carrier. In order to time and interrupt this movement an arm 136, integral with the dog 132 is extended rearwardly and is secured to a spring 137 the opposite end of which in turn is secured to an arm 138, which is integral with and extends downward and rearwardly from the arm 123, so that when the latter is depressed by the wheel 121, the dog 132 is thrown into engagement with the ratchet wheel 130 and operates the same until the arm 123 again raises and releases it.

Brush mechanism.

141 are brushes which polish the back, sides, and extreme toe of the shoe. These brushes are each mounted for rotation, on shafts journalled in bearings 142, and driven through gearing 143, by individual motors 144 (indicated only). Each bearing 142 is carried by a bracket arm 145, to which the motor is also secured. This arm is oscillatably mounted on a pin 146, extending from the members 147. 148 designates a train of gears, such as is ordinarily used on oscillatable-fan motors and is well known, which gears acting through an arm 149, hinged to the frame members 147, slowly oscillate the brushes. The frame members 147 extend horizontally from vertical members 150, to which they are pivoted on pins 151, and are yieldably drawn toward each other by a spring 152. 153, 154 are lugs, which extend upward from a forked

guide 115, between the members 147 and limit the movement of the members 147 toward each other. Each of the vertical members 150 is carried by the forked guide 155, slidably mounted on a rail 156, the two guides being rigidly connected, and adapted for joint reciprocation on these rails, by means of a lever 157, having a fork 158, engaging a pin 159 extending from one of the members 147. 10 The lever 157 is pivotally mounted on a pin 160 carried by a bracket 160^A extending downward from the member 9. 161 is a connecting rod, pivoted to the lever 157 by a pin 162, and to the bevel gear 163 by the crank pin 164. 15 The gear 163 is driven by a bevel pinion 165, which is rotated with a step by step motion, by a ratchet pawl 166, which engages with the ratchet wheel 167. The ratchet pawl is reciprocated by an eccentric 168, mounted on 20 the main driving shaft 58. 169 is a shaft, mounted in bearings 170, which carries pawl trips 171—172 and a trip arm 173. The end of the trip arm 173 extends into the path of a pin 174, which in turn is carried by a ratchet 25 wheel 175. This ratchet wheel is advanced by a ratchet pawl 176 carried by the arm 157, so that when the arm 157 has made a predetermined number of strokes, being one less than the total number of ratchet teeth, the 30 pawl 166 will be disengaged and reciprocation cease. 177, 178 are spring cams, carried by the cross member 179 which act as detents for the ratchet wheel 175 in its alternate shifted positions. When the brush carriage is shifted, after reciprocation of the brushes has ceased, these cams also act to engage a tooth of the ratchet wheel 175, and advance same additionally as the shift is completed to cause the pin 174 to advance past, and release, the 35 arm 173, permitting the pawl 166 to again engage the ratchet wheel 167 and retard the reciprocation of the brushes. The pawl 166 may be normally held in engagement with the wheel by some such means as a tension spring 40 not shown.

Polishing paste and cleaning fluid for brushes.

180 is a second pin, carried by the ratchet 175, which engages the end and 181 of a lever arm which is pivoted on the post 182. To the opposite end 183 of this arm, a cord 184 is connected. The opposite end of the cord 184 is connected to an arm 186, extending laterally from and secured to the lower end of a rod 187, which extends upward and carries a gear 188. The gear 188 meshes with a similar gear 189 and the two gears carry respectively flat trays 190, 191, which are filled with polishing paste. The gears and trays are supported by 55 an arm 192 extending upward from the member 156. 194 is a spring normally acting to keep the trays closed together.

195 is a third pin on the ratchet wheel 175, which pin engages one end of a lever arm 196 mounted on the post 182. From this arm a

cord 197 extends to an arm 198, which is secured on the lower end of a rod 199. This rod extends upward and is secured to the lower end of a tube 200 which is rotatably mounted within a cleaning fluid chamber 201. The tube 200 is provided with vertical slots 202, or holes which are normally out of alignment with perforations 203 in the walls of the outer chamber. When however the arm 198 is shifted by the cord 197 the holes and slots are 75 brought into alignment providing egress for the fluid. 204 is a tube leading from the supply tank 193 to the cleaning fluid chamber.

Cleaning fluid and polishing paste for belts. 80

Extending upward from the arm 111 (Figs. 12, 13 and 14) is an integral post 231 on which is pivoted a tubular arm 232 adapted to swing in a generally horizontal plane. One end of this tubular arm carries and communicates with the interior of a hollow cylindrical cleaning fluid container 233 which is provided with openings 234. 235 is a fluid tank and 236 is a tube from the tank to the arm 232 whereby communication is established from the tank to the cleaning fluid container 233. Encircling the container 233 is a sleeve 237 having openings 238 which do not register circumferentially with the openings 234, but which may be rotated into register therewith. 239 is an arm integral with the sleeve 237 which arm extends into proximity with the arm 111. 240 is a deflecting arm extending from a frame member 4 and having the upper portion 241 thereof bent inward toward the belt 35 to form a deflecting cam. 90

When the arm 111 is swung upward or returns downward the arm 232 is deflected by this cam into contact with the belt 35. At the same time the sleeve arm 239 striking the arm 111 rotates the sleeve bringing the openings 238 into register with the openings 234 and permitting the cleaning fluid to escape into the belt 35. 100

The post 231 extends above the arm 232 and carries pivotally mounted thereon a paste-carrier arm 242, an extension 243 of which extends past the frame members 4 and into the path of an arm 244 which (Fig. 2), is mounted on a pivot 245 and thence extends into the path of the pin 109 on the gear 108. This arm 242 carries a paste container 247, which is rotatably mounted thereon. 248 is an enclosing case, which is carried by an arm 249 extending from the arm 111, within which case the paste container is normally disposed. 250 is a cord attached to the lower side of the paste container and the upper side of the case 248. When therefore, the arm 244 is moved by pin 109 on gear 108 shifts the extension 243, (of the arm 242), away from the frame members 4, the paste container 247 is swung away from the case 248 and being restrained in its movement by the cord 250 is rotated, thus bringing the open side of the container outward and 110 115 120 125 130

the paste contained therein, into contact with the belt 35. 251 is a spring resisting the rotative movement of the container 247 and causing the same to rotate into the case 248 on its 5 return movement.

Referring now to Fig. 2 and Fig. 11, 205 is a coin tube, 206 is a coin detent, which is secured to a stop 207, both being pivoted at 206^A, and the stop 207 being disposed in the 10 path of a lever 208, which lever is pivoted at 209 to the lower side of the seat 34. 210 is a coin in the tube 205, 211 is a coin box. 212 is an extension of the lever 208 beyond the pivot 209. 213 is a cord, or wire, connecting the 15 extension 212 with one arm of a bell crank lever 214, the other arm of which, is connected through a cord 215 with an arm 216^A extending upward from a cross rod 216 which is rotatably mounted in bearings 216^B. 216^C is an arm extending downward from the rod 216, 20 and 216^D, a tension spring from this arm to the post 26.

217 is a trip extending upward from the rod 216 and disposed adjacent to a swinging arm 25 218 hinged to, and depending from, the arm 220^A of a bell crank lever 220. It will especially be noted that while the arm 218 may swing backward, that it has no lateral movement with reference to 220^A, and that the said 30 arm 218 is in the lateral path of the pin 134.

Depending from the lever 220 is a latch 219 having a forwardly turned lower end 219^A extending beneath the extension 136. Extending upward from the lever 220 and integral therewith, is an arm 220^B which engages a pin 221 which projects forwardly from the indicating arm 33.

222 is a contact carried by the lever 220 and insulated therefrom by insulation 222^A. 223 40 is a similar contact plate carried by a bracket extending from the post 26^A and similarly insulated, 224 are circuit wires leading to some suitable source of electric current not shown, and to the motors operating the mechanism, such wiring being of usual form and not necessarily shown or further described. 225 indicates the motor which drives the shaft 58, through any suitable or desired reduction gearing such for instance as a worm and gear. 50

Operation of the machine.

The customer seats himself on seat 34 and places his feet on the foot-rests 32. He presses the foot-rests down and forward 55 against the tension of springs 31 and 30, until the upper edge of the right shoe just touches the indicator arm 33. He drops a suitable coin in the tube 205. The coin travels down the tube 205 and comes to rest 60 against the detent 206 which is fixed to the stop lever 207. The customer presses down on the knob on the lever arm 208, which causes the bottom of the lever arm 208 to hit the top of the coin 210 forcing the stop lever out of 65 the way of the lever arm 208, permitting 208

to move down all the way. The coin is at the same time allowed to fall through the tube 205 into the coin box 211.

As 208 moves down, the other end 212 of the lever moves up carrying the wire 213 with it. 70 This causes the trip 217 to press against the swinging arm 218 deflecting it from the path of the pin 134. This allows the spring 137 acting through the latch 219, to pull down the lever 220 and press the dog 132 into engagement with the ratchet wheel 130. 75

The end of the lever, 220^B, presses against the pin 221, causing the indicator arm 33 to rotate about 33^A and assume the horizontal position. With the indicator arm in this 80 position, the foot-rests are clamped. As the lever 220 comes down the upper contact plate 222 is caused to touch the corresponding plate 223 which closes the circuit of the motors and starts them operating. 85

As the main shaft rotates, the dog 132 causes the ratchet wheel 130 to advance, which shifts the belt-carrier and brush-carrier to one end of their travel, in the position shown in Fig. 5. During the process of shifting, the 90 arm 123 is kept in a horizontal position by means of the bevelled wheel 121. At the end of the travel, the wheel 121 rolls off the track 126, its bevelled edge causes the lug 128 to be deflected, allowing the arm 123 to rise. This 95 releases the tension on the spring 137 so that the dog 132 is disengaged from the ratchet wheel 130, and the shifting operation is stopped. The rise of 123 also causes the projection 123^A to strike the arm 120^A of the latch 120, causing it to oscillate and release the lug 118. This allows the arms 111 and 112 to 100 bear upon the belt holding it taut against the front of the shoe. As the arm 112 comes down, the cleaning fluid container 237 is forced 105 against the cleaning belt 35, by the cam 241. The sleeve arm 239 is deflected by the arm 112, which causes the fluid to flow out of the openings and onto the cleaning belt 35.

As the travel of the brush-carrier ends, the 110 ratchet wheel 175 was advanced by means of the cam spring 177 which caused the pin 174 to advance past and release the arm 173, permitting the pawl 166 to engage the ratchet wheel 167. The belt carrier is now ready to 115 work on the front and top of the left shoe, the brush-carrier is ready to work on the back, sides and toe of the right shoe.

Cleaning and shining front of left shoe.

At the start, the yoke arm 51 is in the position shown in Fig. 1. The belt wheel 54 is caused to revolve with the main drive shaft, by means of the two belts 56 and 59 and the belt wheel 55 and 57 and the swinging arm 41 is oscillated through an arc that lies on the left of its central position (Fig. 1). This causes the cleaning belt 35 to move back and forth across the front of the shoe. This rubs 125 the cleaning fluid into the leather and cleans 130

the front of the shoe. As the arm 41 oscillates, the gear 108 is caused to rotate step by step in a clockwise direction by the pawl 67. When the gear wheel is advanced a predetermined number of steps, the pin 109 deflects the lever 244 which in turn deflects lever 243 opening the polishing paste container and causing polishing paste to be applied to the cleaning belt, and from the belt onto the shoe by the continuous to and fro motion of the belt. The gear 108 makes two revolutions during the process, of cleaning the front of the shoe so that the polishing paste is applied twice.

Shifting from cleaning belt to polishing belt.

At the end of the first clockwise revolution of the gear 108, the pin 109 strikes the arm 84 of the bell crank lever and brings the lever around to the position shown in Fig. 6 so that the arm 85 lies in the path of the pin 109. At the end of the second clockwise revolution of gear 108, the pin 109 strikes the arm 85. During the last step of the revolution the arm 85 strikes the pin 86 and shifts the yoke-arm 80 to its other position. This causes the trip arm 73 to shift to its other position allowing pawl 67 to swing in to rest against the pin 70 and carrying pawl 68 out to a position when it is adapted to engage with the gear 108.

As the arm 85 is shifted during this last step, the ear 90, being integral with the arm 85, turns with it and pushes down the trip lug 99. This depresses the cam 102 and forces out the cam member 103. The arm 104 is thus pushed out against the tension of the spring 105 which exerts a pressure tending to push out the locking member 62. This member does not come out immediately because so long as the pawl 67 acts on the gear 108 there is a pressure exerted on member 62 by the lug 63, which holds this member in place. But when pawl 67 reaches the end of its stroke and starts coming back, the pressure on member 62 is released and this member is pushed out of the path of lug 63. At this point the gear 108 has reached the end of its second clockwise revolution and the arm 41 is in its extreme outer position. It now swings back to its extreme inner or central position and tends to swing back again. But the pawl 67 is now resting against the pin 70 as stated above and hits the gear 108 as arm 41 tends to swing back, which prevents this arm from swinging to the left of its central position. The belt wheel 54 keeps on turning, however, and the locking member 62 being now out of the way, as stated above, the yoke arm 54 is caused to swing to its right or polishing belt position.

The cam 96 strikes the roller 93, deflecting the shift arm 91, which in turn shifts the shaft 81 and the bell crank lever thereon. This causes the ear 90 to slide off the trip lug 99 and thus release the latter which causes the locking pin 62 to tend to resume its former

position, so that when the yoke arm 51 reaches its extreme right position, the pin 62 springs outward into the path of the lug 64, thus locking the yoke arm 51 in its position at the right of the center line of the belt-carrier frame.

70

Polishing front of left shoe.

The swinging arm 41 will now oscillate through an arc lying on the right of its central position which causes the polishing belt 36 to move back and forth across the front of the shoe as the wheel 54 rotates. As the arm 41 oscillates, gear 108 is rotated in a counter clockwise direction by the pawl 68. At the end of the first revolution of gear 108, the pin 109 strikes arm 85 and brings the bell crank lever around so that the arm 84 lies in the path of the pin 109. At the end of the second revolution, the pin 109 strikes the arm 84. During the last step of this revolution, the arm 84 strikes the pin 86 and shifts the yoke-arm 80 to its first position. This causes the trip arm 73 to shift to its first position, allowing pawl 68 to swing to rest against the pin 71 and carrying pawl 67 out to the position shown in Fig. 6, where it is adapted to engage with gear 108.

80

Cleaning and polishing back, sides and extreme toe of right shoe.

95

The cleaning and polishing of the back, sides and extreme toe of the right shoe is accomplished during the same time that the front of the left shoe is being worked on. As the main shaft rotates, the ratchet wheel 167 is rotated with a step by step motion by the pawl 166. The bevel pinion 165, integral with ratchet 167, turns the gear 163 which causes the rotary brushes to have a reciprocating motion with respect to the shoe, the brushes dividing, against the tension of the spring 152, as they strike the shoe and traveling one on each side. The brushes are given a rotary motion by means of the individual motors 144 and an oscillatory motion by the train of gears 148.

100

As the lever 157 swings, the ratchet wheel 175 is rotated by the pawl 176. After one step the pin 195 engages the end of the lever arm 196, which shifts the cord 197 and causes the cleaning fluid to escape from the chamber 202 to be taken up by the rotary brushes as they pass and be deposited on the shoe by these brushes. After a predetermined number of steps (about half the number of teeth on the wheel 175), the pin 180 engages the end 181 of the lever arm 183 pivoted on the post 182, causing the polishing paste trays 190 and 191 to be opened. The brushes then take up some of the paste and apply it to the shoe.

115

When the arm 157 has made a predetermined number of strokes, (one less than the number of teeth on gear 175), the pin 174 strikes the arm 173, rotating the shaft 169 and causing the dog 172 to force the ratchet

120

125

130

pawl 166 out of engagement with the ratchet 167, reciprocation of the brushes ceases and the brushes are left in the position shown in Fig. 2 ready to be shifted to the other shoe.

5 Shifting from one shoe to the other.

When the polishing of the front of the left shoe and the simultaneous cleaning and polishing of the back and sides of the right shoe just described has been accomplished, the gear 108 will have accomplished its second counter clockwise revolution as before described under "polishing front of left shoe" and as there described have tripped arm 73 to shift the pawl 67 into actuating position, and the pawl 68 into engagement with the ends of the teeth on 108 to cause yoke arm 51 to shift about the pin 52 as a center, to its extreme left position. In previously shifting 10 to its right position, shown in Fig. 17, the movement began with the parts as shown in Figs. 15 and 16. In this position the bevelled wheel 121 held the lug 129 displaced, so that the arm 123, urged upwardly by the spring 124 (Fig. 1), brought the trip member 123^A 15 against the arm 120^A, shifted the latch 120 and thereby displaced the trip arm 117 and its lug 118, and at the same time was checked in its upward movement. As then the yoke 20 arm 51 shifted the integral arm 119, carrying the projecting end 119^A, was raised eventually reaching the position shown in Fig. 17. During this movement the trip member 123^A 25 moved upward in engagement with the arm 120^A until the extension 119^A passed above the lug 118 at which time the stop 125 (Fig. 1) stopped the upward movement of the arm 123 and permitted the lug 118 to swing beneath the extension 119^A, and the lug 129 to resume 30 its normal position beneath the wheel 121. When therefore the yoke arm 51 now swings to its left position the roller 121 strikes 35 squarely on the top of the lug 127 and depresses the same so that the latch 123^A does not engage the arm 120^A, and the extension 119^A engages the lug 118, thus depressing trip 40 arm 117 and the continuation 112^A of the arm 112, and thereby raising the end of arm 112, and through the cross arm 116, the corresponding end of the arm 111.

The belt rollers 110 carried by said arms, are thereby raised above the shoe levels. At the same time the depression of the arm 123, just mentioned, causes the spring 137 to 45 throw the dog 132 into engagement with the ratchet wheel 130, rotating it, and thereby, through the pin 134, causing the arm 21 to shift the belt-mechanism to the right shoe, and the brush-mechanism to shift to the left shoe, the wheel 130 making a one-half revolution in doing this. When the new position is 50 reached, the roller 121 will engage the beveled edge of the lug 128 and be deflected thereby, allowing arm 123 to rise and trip 123^A to 55 strike arm 120^A, disengaging lug 118 and al-

lowing arm 123 to rise and disengage dog 132. Thereafter the operation cycle described hereinbefore is repeated on the front of the right shoe and the side and rear of left shoe.

On completion of this operation reverse shift is made as above described under shifting, and the wheel 130 caused to complete the revolution. This will bring the pin 134 to its initial position (Fig. 11). As the pin reaches this position it strikes the arm 218 deflecting the same, and raising arm 220 separating contacts 222 and 223 and stopping operation of the motors.

It will be distinctly understood that the drawings and descriptions are illustrative only, and that various modifications may be made without departing from the spirit of my invention. It will be further understood that I do not wish or intend to limit myself to the details herein shown except in so far as they are specifically set out in the claims.

Having fully described my invention, what I claim and desire to secure by Letters Patent in the United States, is:—

1. In a shoe-polishing machine, the combination with means for polishing with a belt and independent means for polishing with brushes, of dual foot rests, and coordinated means for aligning said belt-means with one of said rests and said brush-means with the other thereof.

2. In a shoe-polishing machine, the combination with means for polishing with a belt and independent means for polishing with brushes, of dual foot-rests, means for aligning said belt-means with one of said rests, and said brush-means with the other thereof, and means for shifting said aligning-means, to reverse the belt-means and brush-means with reference to said rests.

3. In a shoe-polishing machine, a foot rest, a belt having a cleaning-section and a polishing-section, means for positioning said sections alternately with reference to said foot rest, and means for reciprocating said belts in each of said positions.

4. In a shoe-polishing machine, dual foot rests, cleaning-means, polishing-means, means for positioning said cleaning and said polishing-means alternately with reference to one of said rests, means for operating said cleaning-means and said polishing means in each of said positions, and means for positioning said cleaning and polishing means with reference to the other of said rests.

5. In a shoe-polishing machine, dual foot-rests, a belt having a cleaning-section and a polishing-section, means for positioning said sections alternately with reference to one of said rests, means for reciprocating said belts in each of said positions, and means for positioning said cleaning and polishing sections with reference to the other of said rests.

6. In a shoe-polishing machine, dual foot-

- rests, a belt having a cleaning-section and a polishing-section, means for positioning said belt into alignment with one of said rests, and for shifting said sections with reference to said rests, means for reciprocating said belt in each of said shifted positions, and thereafter for aligning said belt with the other of said rests, and shifting and operating the sections in such shifted position.

10 7. In a shoe-polishing machine, dual shoe-rests, a shiftable and reciprocal brush carrier, brushes rotatably carried thereby, means for aligning said brush carrier alternately with each of said rests, and means for actuating said brushes.

15 8. In a shoe-polishing machine, shoe-rests, a shiftable and reciprocal brush carrier, brushes rotatably carried thereby, means for rotating said brushes, means for reciprocating said brush carrier, and means for shifting said brush carrier from alignment with one shoe support into alignment with another thereof.

20 9. In a shoe-polishing machine, shoe-rests, a shiftable and reciprocal brush carrier, brushes rotatably carried thereby, means for rotating said brushes, means for reciprocating said brush carrier, a cleaning fluid reservoir, cleaning fluid within said reservoir, a cleaning fluid chamber, a passage way leading from said reservoir to said chamber, means for applying cleaning fluid to said brushes, and means for shifting said brush carrier from alignment with one shoe rest into alignment with another thereof.

25 10. In a shoe polishing machine, shoe-rests, a shiftable and reciprocal brush carrier, brushes rotatably carried thereby, a cleaning fluid reservoir, cleaning fluid within said reservoir, a cleaning fluid chamber, a passage way leading from said reservoir to said chamber, polishing paste trays, polishing paste with said trays, means for alternately applying cleaning fluid and polishing paste to said brushes, means for rotating said brushes, means for reciprocating said brush carrier, and means for shifting said brush carrier from alignment with one shoe rest into alignment with another thereof.

30 11. In a shoe-polishing machine, a shoe support, a shiftable and reciprocal brush carrier, brushes rotatably carried thereby, actuating means for reciprocating said brush carrier, a cleaning fluid chamber, cleaning fluid within said chamber, polishing paste trays, polishing paste within said trays, and means, controlled by said actuating means, for independently feeding cleaning fluid, and exposing polishing paste, to said brushes.

35 12. In a shoe polishing machine, dual shoe-rests, a shiftable and reciprocal brush carrier, brushes rotatably carried thereby, means for rotating said brushes, means for oscillating said brushes, means for reciprocating said brush carrier, and means for shifting said

carrier alternately into alignment with said shoe-rests.

13. In a shoe polishing machine, transverse rails, a belt-carrier frame shiftable on said rails, means for shifting said frame, a shaft oscillatably mounted on said frame, a drum secured on said shaft, a belt having its ends attached to said drum, a yoke secured to and depending below said shaft, a pin projecting from the lower portion of said frame, an arm oscillatably mounted on said pin and extending upward therefrom, a belt pulley rotatably carried by the upper end of said arm, a crank pin carried by said pulley and engaging said yoke, a second pulley mounted on said pin, means for driving said second pulley, a belt on said pulleys, means for limiting the swing of said arm, means for locking said arm in either extreme position of swing, means for releasing said locking means, a shift gear mounted for rotation on said frame adjacent said drum shaft, ratchet pawls carried by the upper end of said yoke, alternately usable for advancing said gear in opposite directions, means for shifting said pawls alternately into engagement with the said gear, and means actuated by the rotation of said gear for controlling said pawl shift.

14. In a shoe polishing machine, a belt-carrier frame transversely shiftable, means for shifting said frame, a shaft oscillatably mounted on said frame, a drum secured on said shaft, a belt having its ends attached to said drum, a yoke secured to and depending below said shaft, a pin projecting from the lower portion of said frame, an arm oscillatably mounted on said pin and extending upward therefrom, a belt pulley rotatably carried by the upper end of said arm, a crank pin carried by said pulley and engaging said yoke, a second pulley mounted on said pin, means for driving said second pulley, a belt on said pulley, means for limiting the swing of said arm, means for locking said arm in either extreme position of swing, means for releasing said locking means, a shift gear mounted for rotation on said frame adjacent said drum shaft, ratchet pawls carried by the upper end of said yoke, alternately usable for advancing said gear in opposite directions, means for shifting said pawls alternately into engagement with the said gear, and means actuated by the rotation of said gear for controlling said pawl shift.

15. In a shoe polishing machine, a belt carrier frame transversely shiftable, means for shifting said frame, a shaft oscillatably mounted in said frame, a drum secured on said shaft, a belt having its ends attached to said drum, a yoke secured to and depending below said shaft, a pin projecting from the lower portion of said frame, an arm oscillatably mounted on said pin and extending upward therefrom, a belt pulley rotatably carried by the upper end of said arm, means for

- driving said pulley, a crank pin carried by said pulley and engaging said yoke, means for limiting the swing of said arm, means for locking said arm in either extreme position 5 of swing, means for releasing said locking means, a shift gear mounted for rotation on said frame adjacent said drum shaft, ratchet pawls carried by the upper end of said yoke, alternately usable for advancing said gear in 10 opposite directions, means for shifting said pawls alternately into engagement with the said gear, and means actuated by the rotation of said gear for controlling said pawl shift.
- 15 16. In a shoe polishing machine, a belt-carrier frame transversely shiftable, means for shifting said frame, a shaft oscillatably mounted in said frame, a drum secured on said shaft, a belt having its ends attached to said drum, a yoke secured to and depending below said shaft, a pin projecting from the lower portion of said frame, an arm oscillatably mounted on said pin and extending upward therefrom, a crank arm and pin rotatably carried by the upper end of said arm, said pin engaging said yoke, means for rotating said crank arm, means for limiting the swing of said oscillatable arm, means for locking said arm in either extreme position 20 of swing, and means for releasing said locking means.
- 25 17. In a shoe polishing machine, a belt carrier frame, a shaft oscillatably mounted in said frame, a drum on said shaft, a belt having its ends attached to said drum, a yoke secured to and depending below said shaft, a pin projecting from the lower portion of said frame, an arm oscillatably mounted on said pin and extending upward therefrom, a crank arm and pin rotatably carried by the upper end of said arm, said pin engaging said yoke, means for rotating said crank arm, means for limiting the swing of said oscillatable arm, means for locking said arm in either extreme position 30 of swing and means for releasing said locking means.
- 35 18. In a shoe polishing machine, a belt carrier frame, a shaft oscillatably mounted in said frame, a drum on said shaft, a belt having its ends attached to said drum, a yoke secured to and depending below said shaft, a pin projecting from the lower portion of said frame, an arm oscillatably mounted on said pin and extending upward therefrom, a crank arm and pin rotatably carried by the upper end of said arm, said pin engaging said yoke, means for rotating said crank arm, means for limiting the swing of said oscillatable arm, means for locking said arm in either extreme position 40 of swing, means for releasing said locking means, a shift gear mounted for rotation on said frame adjacent said drum shaft, ratchet pawls carried by the upper end of said yoke, alternately usable for advancing said gear in opposite directions, means for shifting said pawls alternately into engagement with the said gear, and means actuated by the rotation of said gear for controlling said pawl shift.
- 45 19. In a shoe polishing machine, a frame having transverse rails, a carrier frame shiftable on said rails, polishing belt mechanism carried thereby, means for shifting said belt frame along said rails, means for initiating said shift movement, and means for stopping 50 said shift movement.
- 55 20. In a shoe polishing machine, a frame having transverse rails, a carrier frame shiftable on said rails, polishing belt mechanism carried thereby, means for shifting said belt frame forward and backward along said rails, means for initiating said shift movements, and means for stopping said shift movements.
21. In a shoe polishing machine, an oscillatable drum, a belt, comprising a cleaning section and a polishing section, said belt having its ends secured to said drum, a shoe rest below said belt, an idler pulley on each side of said rest and disposed below the level of said shoe rest, under which said belt passes, 55 means for rotatively shifting said drum to alternately bring said cleaning section and polishing section over said foot rest and means for oscillating said drum in each of said shifted positions.
22. In a shoe polishing machine, an oscillatable drum, a belt, comprising a cleaning section and a polishing section, said belt having its ends secured to said drum, spaced idler pulleys around which said belt passes 60 dual shoe rests, means for raising said pulleys above said shoe rests, means for shifting said belt assembly alternately over each of said shoe rests, means for depressing said idler pulleys after said shift, means for rotatively shifting said drum to alternately bring said cleaning section and polishing section into operative relation to the foot rest after said shift, and means for oscillating said drum in each of said shifted positions.

In testimony of the foregoing, I affix my signature.

JACOB HOFFMAN.
